FUSE SETTING MECHANISM

Otto R. Haas, Beverly, Mass., assignor to United Shoe Machinery Corporation, Flemington, N. J., a corporation of New Jersey

Application January 31, 1945, Serial No. 575,514

10 Claims. (Cl. 89—6)

1

This invention relates to ordnance and more particularly to mechanisms for setting the fuses of rounds of ammunition.

An object of the invention is to provide a knife-type fuse setter which is automatically adjustable to act on rounds having projectiles the shapes of which are not all identical. To this end and as a feature of the invention the fuse setter comprises a set of knives engageable with the round of ammunition rearwardly of the fuse ring during the fuse-setting operation to hold the round against rotation and another set of knives engageable with the fuse ring of the round and being rotatable to turn the fuse ring. The latter set of knives is carried by a rotatably mounted fuse-cutter head mounted for axial movement toward and from a round of ammunition. The first set of knives is mounted for rectilinear movement with the fuse-cutter head, there being equalizer connections between the two sets of knives permitting movement of the two sets in equal and opposite directions whereupon the forces with which the knives engage the round are always uniform.

Another object of the invention relates to the provision of improved means for automatically terminating the fuse-setting operation after the fuse has been set a predetermined amount. This is accomplished in accordance with a further feature of the invention by mounting a stop arm on the rotatable shaft supporting the fuse-cutter head, this stop arm cooperating with a control arm positioned by the operator in accordance with the desired amount of fuse-setting. The control arm has a portion which lies in the path of movement of a member carried by the stop arm so that after the fuse-cutter head has rotated a predetermined amount, determined by the position of the control arm, the rotation of the shaft will be arrested by engagement with the control arm of the member carried by the stop arm. The fuse-cutter head is driven by an electric motor, the circuit to which is controlled by a switch actuated by an arm pivoted on the control arm. Upon movement of the stop arm into its final position as determined by the position of the control arm the switch actuating arm is moved by a member carried by the stop arm thereby actuating the switch to interrupt the operation of the motor.

The above and other features of the invention, including various novel combinations of parts and details of construction, will now be described in detail by reference to the accompanying drawings and pointed out in the claims.

2

In the drawings,

Fig. 1 is a side elevation, partly in section, of one form of fuse-setting mechanism in which the invention is embodied;

5 Fig. 2 is a section on the line II—II of Fig. 1;
 Fig. 3 is a section on the line III—III of Fig. 2;
 Fig. 4 is a section on the line IV—IV of Fig. 2;
 Fig. 5 is a section on the line V—V of Fig. 4;
 Fig. 6 is a section on the line VI—VI of Fig. 1;
 Fig. 7 is an end elevation of the mechanism shown in Fig. 6;

10 Fig. 8 is a section on the line VIII—VIII of Fig. 1;

Fig. 9 is a section on the line IX—IX of Fig. 6;

15 Fig. 10 is an elevation of the control arms associated with the fuse-setting mechanism, and

Fig. 11 is an elevation of a switch actuated by the fuse-setting mechanism at the conclusion of the fuse-setting operation.

20 The fuse-setting mechanism illustrated herein is embodied in a gun-loading mechanism of the type shown and described in Letters Patent of the United States No. 2,417,300, granted March 11, 1947, on an application filed in the name of 25 Chester W. Greene. The fuse-setting mechanism is carried by a support 10 (Fig. 1) extending between and secured to the arms of the carriage shown in that patent forwardly of a rounds magazine 12.

30 The fuse-setting mechanism comprises a set of four knives 14 (Fig. 2) arranged to engage the nose of a round 16 rearwardly of a fuse ring 18 for locking the round against rotation during the fuse-setting operation, and a second set of knives 20 engageable with the fuse ring of the round. The knives 20 are carried by a ring 22 which is rotatable to set the fuse a predetermined amount. The knives 14 are carried by a support 24 arranged for sliding movement toward and away

35 40 from the magazine 12 in which the round 16 is positioned for the fuse-setting operation. For thus carrying the support 24, four rods 26 are provided, the upper rods being carried at their rearward ends by the forward portion of the magazine 12 and at their forward ends by a gear housing 28 carried by the support 10. The lower rods 26 are carried at their forward ends by the support 10 and at their rearward ends by a plate 30 extending upwardly from a bracket 32 extending rearwardly from the support 10. The knives 14 are adjustably carried by the support 24 as shown in Fig. 3 by bolts 34 provided with eccentric portions 36 engageable with apertures in vertical extensions of the knives 14. Nuts 38, engageable

45 50 55 with a ring-shaped plate 40, serve to hold the

plate against the forward wall of the support 24 and to lock the bolts 34 in the proper positions of adjustment.

The fuse-setting knives 20 are formed on the inner surface of the ring 22 to the forward side of which are secured three forwardly extending bars 42 (Figs. 2 and 4) slidable in a fuse-setter head 44 which is in turn carried for sliding movement on a splined shaft 46 extending rearwardly from the gear housing 28 and connected through suitable reduction gearing to a fuse-setter motor 48. The ring 22 is urged rearwardly of the head 44 by springs 50 (Fig. 4) acting between the forward ends of the bars 42 and a flanged sleeve 52 secured to the front of the fuse-cutter head 44. The bars 42 are formed with rack teeth 54 engaged by gears 56 journaled in the head 44. The gears 56 also engage rack teeth formed on sliding bars 60, the rearward portions of which are provided with lugs 62 slidable in slots formed in the head 44. The lugs 62 are grooved to receive the ring-shaped plate 40 (Figs. 1 and 3). From the above it will be understood that the support 24, carrying the knives 14, is connected by the plate 40 and bars 60 to the head for movement therewith toward the round at the beginning of the fuse-setting operation. After the knives 14 have engaged the round, further rearward movement of the head 44 will cause the ring 22 to move rearwardly relatively to the head 44. This is caused by the fact that the head 44 will move rearwardly after the support 24 has come to rest with the knives 14 in engagement with the round and the relative movement between the bars 60 and head 44 will cause rotation of the gears 56 to cause rearward movement of the bars 42 relatively to the head 44 until the knives 20 have engaged the fuse ring of the round. By this arrangement the force with which the two sets of knives engage the round is equalized and the knives may be used with projectiles of the different shapes frequently encountered without the necessity of any manual adjustment of the parts of the fuse setter.

For thus moving the head 44 to carry the knives into fuse-setting engagement with the round, a cam shaft 64 is provided with a cam 66 with which cooperates a cam roll 68 carried by a bell crank lever 70 mounted on a shaft 72 carried by and extending outwardly of the gear housing 28. Also carried by the shaft 72 is a downwardly extending arm 74 connected by an adjustable link 76 to a lever 78 pivoted at 80 to the support 10. The upper end of the lever 78 is forked and carries rolls 82 engageable in the groove of the flanged sleeve 52. A spring 84, acting between an upwardly extending arm of the bell crank lever 70 and a bracket 86, secured to and extending upwardly from the support 10, moves the head 44 rearwardly when the cam 66 is in the position shown in Fig. 1 thereby to force the knives 14 and 20 onto the nose of the round. At the conclusion of the fuse-setting operation the cam 66 is rotated by the shaft 64 in the direction of the arrow as described in the above-mentioned Greene patent and after a slight amount of rotation of the cam, the bell crank lever 70 is rocked in a counterclockwise direction whereupon the head 44 is moved forwardly to carry the knives 14 and 20 out of engagement with the nose of the round.

For controlling the amount of the fuse-setting operation the splined shaft 46 extends forwardly of the gear housing and carries at its forward end

a stop arm 90 (Figs. 6, 7 and 10). The initial position of the stop arm is determined by an adjustable stop screw 92 against which the arm bears when the fuse setter is in its zero or starting position. At this time a switch 94, depending from a plate 96, secured to gear housing 28 and extending laterally therefrom, is held in one position by a switch-actuating plate 98 carried by the outer end of the stop arm 90. A control arm 100 (Figs. 9 and 10) is mounted adjacent to and just forwardly of the stop arm 90 on a shaft 102 (Fig. 9) which is driven through reduction gearing by a motor 104 (Fig. 8) which is in turn controlled by the operator by the use of suitable equipment for positioning the control arm 100 in accordance with the desired amount of fuse setting. One type of equipment that may be employed is a self-synchronous transmission system such as that illustrated and described in the 20 Hewlett et al. Reissue 16,667, granted July 5, 1927. Inasmuch as this equipment forms no part of the present invention, it is not illustrated herein. The control arm is provided with a rearward extension 106 arranged in the path of movement of an adjustable stop screw 108 (Fig. 6) carried by the stop arm 90. Pivoted secured to the rear side of the control arm 100 is an arm 110, the lower end of which is formed as a gear segment engageable with teeth 112 (Figs. 9 and 10) in the 25 outer end of a rod 114 slidable in a bore formed in the forward end of the shaft 46. The rod 114 is urged outwardly of the shaft 46 by a spring 116. The upper end of the arm 110 is formed with a projection 118 having a cam surface arranged 30 to be engaged by the round end of a screw 120 adjustably carried by the stop arm 90. Accordingly, when the head 44 has been rotated a predetermined amount, according to the position of the control arm 100, the screw 120 engages the upper 35 end of the arm 110 and rocks it in a clockwise direction as viewed in Fig. 1 thus moving the rod 114 rearwardly of the shaft 46 against the force of the spring 116. This motion of the rod 114 is transmitted through a segment 122 pivoted on a shaft 40 45 124 (Fig. 11) journaled in a sleeve 126 (Fig. 8) carried by a gear housing 128 to a switch actuating arm 130 to actuate a switch 132. This switch is operated at the conclusion of the fuse-setting 50 operation to open the circuit to the fuse-setter motor at the same time that the screw 120 engages the upper end of the control arm 100 positively to arrest the movement of the arm 90 and rotation of the shaft 46.

Carried by the support 10 is a switch 140 (Figs. 55 1 and 8), the function of which is to reverse the fuse-setter motor at a predetermined time after the conclusion of the fuse-setting operation in order to return the stop arm 90 to its original position as shown in Fig. 6. For operating the 60 switch 140, a switch arm 142 (Fig. 1) is pivoted on a bracket 144 depending from the support 10 and is provided at its lower end with a cam roll 146 received in a groove 148 of a cam 150 carried by the cam shaft 64.

At the beginning of the fuse-setting operation the parts are in the positions shown in Fig. 1 with the knives 14 and 20 in engagement with the nose of the round, the parts being at rest. The control arm 100 is positioned by the motor 104 which is in turn operated by suitable control mechanism (not shown) in accordance with the desired amount of fuse setting. After the arm 100 has been properly positioned the operator closes a circuit to the fuse-setter motor whereupon the shaft 46 is rotated to turn the ring 22 carrying the knives 20, 70 75

thereby turning the fuse ring with respect to the round 16. The fuse-setter motor continues to rotate until the stop arm 90 moves to a position determined by the position of the control arm whereupon the screw 120 engages the cam surface of the projection 118 carried by the arm 110, rocking this arm about its pivot and causing actuation of the switch 132 as heretofore described which opens the circuit to the fuse-setter motor. The screw 108 carried by the stop arm 90 engages the projection 106 of the control arm 100 at the same time, thereby positively stopping the rotation of the shaft 46, bringing the fuse-cutter head 44 to rest.

The actuation of the switch 132 operates suitable mechanism such as that described fully in the Greene patent referred to above, to start operation of the cam shaft 64. At the initial portion of the rotation of the cam 66 the bell crank lever 70 is rocked in a counterclockwise direction thereby withdrawing the fuse-cutter head from engagement with the nose of the round. The further rotation of the cam shaft causes the round to be transferred from the magazine and loaded into the gun as described in the Greene patent. Immediately after the fuse-cutter head has been withdrawn from the nose of the round, the switch arm 142 is operated to actuate the switch 140 closing a circuit which causes reversal of the fuse-setter motor which rotates to return the stop arm 90 to the position shown in Fig. 6. When the arm reaches this position the switch 94 is actuated to open the circuit to the fuse-setter motor. After a new round has been indexed in the magazine into the position shown in Fig. 1 and the cam 66 has completed substantially a revolution the cam follower 68 drops into the recess in the periphery of the cam whereupon the spring 84 forces the fuse-cutter head into engagement with the nose of the new round. This action of the fuse-cutter head causes the knives 14 to engage the round rearwardly of the fuse ring after which the knives 20 move relatively to the head 44 by reason of the equalizer connections heretofore described so that the two sets of knives engage the respective portions of the round with equal forces. It will be understood that the shape of the nose of the round may be such that the two sets of knives will engage the round at the same time, or the knives 20 might engage the fuse ring prior to engagement of the knives 14 with the round rearwardly of the fuse ring. In any event, regardless of the exact shape of the nose of the round, the equalizer connections between the two sets of knives insure proper engagement with the respective portions of the round with the same forces. With the fuse-cutter head in the position shown in Fig. 1 the parts come to rest and the mechanism is ready for the next fuse-setting operation.

Having thus described my invention, what I claim as new and desire to secure by Letters Patent of the United States is:

1. Fuse-setting mechanism comprising a set of knives engageable with a round to hold it against rotation and a second set of knives engageable with the fuse ring of a round, means for causing the application of equal pressures by said two sets of knives on the round, and means for moving said second set of knives relatively to the first set to effect a fuse-setting operation.

2. Fuse-setting mechanism comprising two sets of knives engageable with different portions of the nose of the round, means for moving one of the sets of knives relatively to the other to

set the fuse of the round, means for moving said knives into engagement with the nose of the round, and means connecting said sets of knives for relative movements toward and away from each other whereby the pressures exerted by said knives on the nose of the round are equalized.

3. Fuse-setting mechanism comprising a set of knives engageable with a round to hold it against rotation during the fuse-setting operation, a second set of knives engageable with the fuse ring of the round, means interconnecting said sets of knives for movements toward and away from each other whereby the pressures exerted by said knives on the round are equalized, and means for turning said second set of knives relatively to the first set.

4. Mechanism for setting the fuses of rounds comprising a fuse-cutter head, knives carried by said head engageable with the fuse ring of a round for rotating the fuse ring in response to rotation of the head, means mounting said knives in said head for axial movement relatively thereto, a second set of knives engageable with the round to hold it against turning during the fuse-setting operation, and pressure equalizing connections between said first and second sets of knives so that equal forces are exerted by both sets of knives on the round.

5. In combination, a fuse-cutter head, means for moving said head toward and from a round supported in alinement therewith, a set of knives carried by said head for rotation therewith and engageable with the fuse ring of a round, means mounting said knives in said head for axial movement relatively thereto, a second set of knives mounted in advance of said first set of knives, means connecting said second set of knives for rectilinear movement with said head, said connecting means including a connection to said first set of knives arranged to permit relative axial movement of said sets of knives in opposite directions, and means for rotating said head.

6. Mechanism for setting the fuses of rounds comprising first and second sets of knives engageable respectively with a round rearwardly of the fuse ring and with the fuse ring, means for moving said knives into engagement with a round, a head supporting said second set of knives for rotation relatively to the first set, means connecting said first set of knives to said head for rectilinear movement relatively thereto and to said second set of knives, and means for rotating said head.

7. In combination, a fuse-cutter head, a set of knives rotatable with said head, a second set of knives, means constraining said second set of knives against rotation with said head, means for imparting rectilinear movement to said head and to said sets of knives, and means connecting said sets of knives for equal and opposite movements axially of the head and relatively to each other.

8. Fuse-setting mechanism comprising a fuse-cutter head, means for rotating said head to set the fuse of a round, a control arm arranged to be positioned in accordance with the desired amount of fuse setting, a stop arm arranged to be turned by said rotating means concomitantly with the rotation of said head, means carried by said stop arm engageable with said control arm after the fuse has been set an amount depending upon the setting of the control arm, and a switch actuated by said stop arm simultaneously with the engagement of said means with the control

arm for interrupting the operation of said rotating means.

9. Fuse-setting mechanism comprising a fuse-cutter head, means for rotating said head to set the fuse of a round, a control arm arranged to be positioned in accordance with the desired amount of fuse setting, a stop arm arranged to be turned by said rotating means concomitantly with the rotation of said head, means carried by said stop arm engageable with said control arm after the fuse has been set an amount depending upon the setting of the control arm to interrupt the rotation of the fuse cutter head, a switch controlling the operation of said rotating means, a switch actuating arm pivotally carried by said control arm, and means carried by said stop arm for moving said switch actuating arm to interrupt the operation of said rotating means simultaneously with the engagement of the means carried by the stop arm with the control arm.

10. Fuse-setting mechanism comprising a fuse-cutter head, a shaft supporting said head for rotation and for rectilinear movement relatively thereto, a motor for turning said shaft, means

for moving said fuse-cutter head along said shaft to engage the nose of a round the fuse of which is to be set, a stop arm carried by said shaft and rotatable therewith, a control arm having a portion lying in the path of movement of the stop arm and arranged to be positioned in accordance with the amount of fuse setting required whereby the engagement of the stop arm with the control arm terminates the rotation of said shaft and the fuse-cutter head, a switch controlling the operation of said motor, and means carried by said control arm engageable by said stop arm at the end of the fuse-setting operation for actuating said switch to interrupt the operation of said motor.
